UNITED STATES PATENT OFFICE.

WILLIAM H. BAKER, OF CENTRAL FALLS, RHODE ISLAND, AND FREDERIC E. KIP, OF MONTCLAIR, NEW JERSEY.

DESIGN FOR A DROP FOR USE IN ELECTRICAL WARP STOP-MOTIONS.

SPECIFICATION forming part of Design No. 29,682, dated November 15, 1898.

Application filed October 25, 1898. Serial No. 694,554. Term of patent 14 years.

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented a new and original Design for a Drop for Use in Electrical Warp Stop-Motions, of which the following is a specification, reference being had to the accompanying drawings, forming a part thereof.

In said drawings, Figure 1 is a side elevation or face view of our design, and Fig. 2 is an edge view of the same.

15 The leading feature of our design consists in the elongated longitudinally-slotted body portion having a laterally-projecting portion which extends part way across the slot from one lateral margin thereof and is upwardly inclined from base to extremity, and said body

having in its edge above said slot a niche or recess.

A is the body portion of the drop. a is the longitudinal slot therein.

b is the lateral projection from one side of the slot and having an incline or sloping contour at b', and c is the niche or recess in the edge of the body A above the slot therein.

What we claim is—

The design for a drop for use in electrical warp stop-motions, substantially as herein shown and described.

In witness whereof we have hereunto signed our names, this 22d day of October, 1898, in the presence of two subscribing witnesses. 35
